UNITED STATES PATENT OFFICE.

JEAN CHARLES DIEDERICHS, OF BOURGOIN, FRANCE.

WEFT-END-CONTROLLING MEANS FOR WEFT-REPLENISHING MECHANISM.

1,058,128.

Specification of Letters Patent. Patented Feb. 11, 1913.

Application filed June 22, 1910. Serial No. 568,410.

To all whom it may concern:

Be it known that I, JEAN CHARLES DIEDERICHS, a citizen of the Republic of France, and a resident of Bourgoin, Isère, France, have invented a new and useful Improved Weft-End-Controlling Means for Weft-Replenishing Mechanism, of which the following is a specification.

This invention relates to an improved pirm magazine with automatic distributor for automatically changing the pirm in the shuttle of automatic looms, and is illustrated by way of example in the accompanying drawing in which:—

Figures 1 and 2 are sectional end elevations on the lines 1, 1 and 2, 2 respectively in Fig. 3. Fig. 3 is a front elevation with part cut away. Figs. 4 and 5 represent in longitudinal section and in cross section respectively the arrangement of a device for drawing out the reserve of thread at the end of the pirm preparatory to introducing the latter into the shuttle. Fig. 6 represents a development of a helicoidal groove serving to operate the pincers for unwinding the reserve of thread from the pirm.

In this drawing A represents a magazine which comprises vertical grooves a' , a^2 , a^3 , a^4 , a^5 , . . . converging at their base toward a central point b corresponding to the axis of oscillation of a register distributor device B.

The register distributor B comprises a part forming a register b' rigid with a tubular part b^2 brought and held successively in alignment with the vertical grooves a' , . . . a^5 by a ratchet b^3 and a pawl b^4 rigid with an arm b^5 upon which there acts another arm c' mounted loosely on a spindle c of a barrel C and also furnished with a pawl c^2 engaging with a ratchet wheel c^3 rigid with the barrel C likewise mounted freely upon the spindle c . The register b' acted upon by a spiral spring in the direction indicated by the arrow a (Fig. 1) carries a finger b^6 with which recesses a^6 formed in the partitions of the magazine A correspond in such a manner that this finger always bears upon the first pirm at the base of the groove a' and passes in succession from one conduit to the other in succession as they are exhausted.

Beneath the shaft b there is vertically arranged a passage b^7 , the upper opening of which corresponds with the base of the tubular part b^2 while the cavities c^3 of the

barrel C are displaced beneath its lower opening. Simultaneously with the passage of the cavities c^3 beneath the passage b^7 the latter receives a pirm y . These pirms are sustained by a guide d during their circular transportation with the barrel C.

Each pirm is provided with a plug e inserted and frictionally held in the hollow end thereof. On the plug is wound in any desired manner a reserve of the pirm thread, which is drawn out, (in a manner about to be described) in extension of the pirm preparatory to introducing the latter into the shuttle.

At the moment at which the pirm is introduced into the cavity of the barrel the end of the pirm which carries the reserve of thread engages in a recess in a plate C' rigid with the barrel C and the plug e or the reserve of thread e' is seized by a pair of pincers F formed of a fixed arm f and a pivoted arm f' , these two parts being threaded upon a shaft f^2 upon which they slide longitudinally under the influence of a groove f^3 formed in a fixed drum f^4 and in which a nose f^5 of the pincers is engaged.

The pivoted part f' of the pincers F is maintained closed upon the part f by a spiral spring f^6 wound around a sleeve rigid with the part f of the pincers and supported by a ring fixed to the end of the said sleeve and enabling the tension of the spring to be adjusted.

As shown by the development of the drum f^4 in Fig. 6 the groove f^3 comprises two concentric parts 1—2 and 6 opposite each of which there are arranged a boss f^7 f^8 and two helicoidal parts 3—4—5 and 7—8—9—10.

The apparatus comprises as many pincers F as there are cavities in the barrel C sliding upon the corresponding number of shafts f^2 arranged around the drum f^4 fixed by their ends between two plates C' and C^2 rotating integrally with the barrel C, while the said drum f^4 remains fixed.

The operation of the device described above is as follows: The magazine A being filled with pirms y and the loom started, when the weft becomes exhausted in front of the weft stop-motion a special known mechanism causes the movement of the hammer z which introduces the pirm y situated at the base of the barrel C and held by the stop z' into the shuttle w of the loom. The barrel being no longer supported by the bearing of the pirm y against the stop

z' becomes subject to the action of the arms c' and b^5 which by their weight displace the barrel which is already acted upon by the weight of the pirns with which it is loaded; 5 its movement is arrested by the bearing of the following pirn against the stop z' ; at this moment an empty cavity presents itself at the base of the passage b^7 into which a pirn falls. In their travel with the barrel 10 and at the base thereof the pirns are supported by their nose engaged in a guide d from which they escape when expelled by the hammer z . At each movement of the lever c' the lever b^5 rocks and the dog b^4 releases the ratchet wheel b^3 which acted upon by a spiral spring wound around its shaft is free to rotate in the direction indicated by the arrow x if the finger b^6 is liberated by the escape of the last pirn from one of 20 the grooves a' a^2 . . . . The lever c' is lifted by a roller c^4 mounted upon the lay of the loom and its pawl c^2 maintains it cocked for the ratchet c^3 ready to drive the barrel as soon as the hammer z expels the 25 shuttle located at its base. The pirns in falling into the cavities and the recesses in the barrel c and the plate c' engage their plugs e in the pincers F which are opened at this moment by the boss f^7 . As the barrel 30 rel rotates, the pincers close after having escaped from the boss f^7 , seize the plug e and draw the latter out therewith as the said pincers F are displaced longitudinally upon the shaft f^2 , by the helicoidal groove f^1 in the drum f^4 , so that the plugs e occupy in succession the positions 3, 4 and 5 and finally reach the position 6. In this position the weft thread (Fig. 3) is arranged in line with the path of the shuttle, so that 40 when the pirn is inserted in the shuttle the latter is threaded. After having traversed the positions 6 and 7 the arm f' of the pincers F encounters another boss f^8 which opens the pincers so as to release the plug e 45 and the latter then falls into a receptacle arranged below.

What I claim and desire to secure by Letters Patent of the United States is:—

1. A weft replenishing device for looms, 50 comprising a rotary feed cylinder adapted to carry a supply of pirns, gripping devices for drawing out in succession from the several pirns a reserve of thread arranged at the end of each thereof, and cam means for 55 moving certain of said gripping devices serially and simultaneously in extension of the pirns to draw out said reserves of thread for the purpose specified.

2. A weft replenishing device for looms, comprising an automatic feed cylinder 60 adapted to carry a supply of pirns in combination with a series of pincers arranged at one end of said feed cylinder and rotating therewith, means to longitudinally displace said pincers during said rotation and means 65 to open the same at the beginning and at the end of their longitudinal displacement, for the purpose described.

3. A weft replenishing device for looms, comprising an automatic feed cylinder 70 adapted to carry a supply of pirns in combination with a series of pincers arranged at one end of said cylinder and rotating therewith, and a stationary member with helicoidal guideway engaged by said pincers 75 whereby the latter are longitudinally displaced, substantially as described.

4. A weft replenishing device for looms, comprising an automatic feed cylinder adapted to carry a supply of pirns in combination with a series of pincers arranged at one end of said cylinder and rotating therewith, and a stationary member with helicoidal guideway engaged by said pincers whereby the latter are longitudinally 80 displaced, said pincers comprising a fixed arm provided with a claw engaging said helicoidal guideway and a movable arm pivoted to said fixed arm and a spring tending to keep said pivoted arm closed upon 85 the fixed arm, substantially as described.

5. A weft replenishing device for looms, comprising an automatic feed cylinder adapted to carry a supply of pirns in combination with a series of pincers arranged 90 at one end of said cylinder and rotating therewith, and a stationary member with helicoidal guideway engaged by said pincers whereby the latter are longitudinally displaced, said pincers comprising a fixed arm 95 provided with a claw engaging said helicoidal guideway and a movable arm pivoted to said fixed arm and a spring tending to keep said pivoted arm closed upon the fixed arm, together with stops arranged at the 100 extremities of said helicoidal guideway adapted to engage and temporarily open said pivoted arm, for the purpose described.

In testimony whereof I have signed my name to this specification, in the presence 110 of two subscribing witnesses.

JEAN CHARLES DIEDERICHS.
